UNITED STATES PATENT OFFICE.

JOHN C. TATE, OF OAKLAND, CALIFORNIA.

PORABLE HEATER.

1,326,222.

Specification of Letters Patent. Patented Dec. 30, 1919.

Application filed September 21, 1916. Serial No. 121,481.

To all whom it may concern:

Be it known that I, JOHN C. TATE, a citizen of the United States, residing at Oakland, in the county of Alameda and State 5 of California, have invented certain new and useful Improvements in Portable Heaters, of which the following is a specification.

The present invention relates to a stackless heater, adapted for the burning of 10 liquid or gaseous fuel, and by the use of which the air within the room or inclosure in which the heater is positioned will not become fouled or contaminated, due to the fumes of the products of combustion rising 15 from the heater.

The invention has for its principal objects to provide a heater having a receptacle or 20 container removably positioned preferably in each of the heating chambers thereof, 25 within the path of the rising products of combustion, and adapted to contain or hold a suitable chemical compound or material capable of absorbing the impurities and 30 moisture from the products of combustion prior to their escaping from the heater to the atmosphere, and to provide a heater 35 wherein the absorbing compound may be readily removed therefrom and renewed when desired, and through which the products 40 of combustion are required to pass prior to escaping from the heater.

With the above mentioned and other objects in view, the invention consists in the novel construction and combination of parts 45 hereinafter described, illustrated in the accompanying drawings, and pointed out in the claims hereto appended, it being understood that various changes in the proportion, form, size and minor details of construction 50 within the scope of the claims may be resorted to without departing from the spirit or sacrificing any of the advantages of the invention.

To more fully comprehend the invention, 55 reference is directed to the accompanying drawings, wherein—

Figure 1 is a view in side elevation of the preferred embodiment of my heater, disclosing the tops of the heating chambers 50 which permit the positioning of the containers with the compound within the heater.

Fig. 2 is a view in end elevation of the heater disclosed in Fig. 1, illustrating one of the outlets for the purified products of combustion.

Fig. 3 is a fragmentary sectional view of

Fig. 1 showing two heating chambers, one being filled with a purifying material and intact, while the other has the material and covering cap removed therefrom. 60

Fig. 4 is a modified form of support for the purifying material.

Fig. 5 is a view in plan of the modified form of support.

Referring more particularly to the several views of the drawings, wherein like characters of reference designate corresponding parts,—1 indicate the sections of a suitable heater of the radiator type, and said sections connect preferably at their base through 65 alined openings 2, through which the fuel pipe 3, provided with the burner openings 4, passes.

Each section is provided with a combustion chamber 5, at the base thereof, which 70 communicates with the heating chamber 6 at the upper portion of the section. The air required for combustion is preferably admitted through an opening 7 below the combustion chamber. A removable head 8 is positioned over and closes the upper portion 75 of the heating chamber, and the same is provided with outlet openings 9 in opposite sides of the wall thereof. Suitable baffle walls 10 extend inwardly and upwardly 80 from the bottom and side edges of the openings 9 and project a distance above the upper edge thereof, thereby providing a retarding wall or baffle for the products of combustion rising in the heating chamber, 85 before the same are released or pass to the atmosphere. To insure the rigid seating of the head 8 onto the peripheral wall 11 of the heating chamber casing, an annular inwardly extended offset 12, having the downwardly projecting portion 12', is provided 90 at the lower edge of the head, and when the head is in position, as in Fig. 2, the outer face of the portion 12' extends a slight distance below the upper edge of the wall 11 95 100 in contact with the inner surface thereof, and with the lower edge resting on a suitable annular flange 13 projecting inwardly from the wall 11 a slight distance between the upper edge thereof.

Removably positioned within the heating chambers 6, through the openings provided by the removing of the heads 8, are the suitable baskets or containers 14, preferably of open mesh material, and the same are each 110 preferably provided with a handle 15 to facilitate the removing of the same from with-

in the chambers. The baskets or containers are supported within the heating chambers in any suitable manner, preferably by the inwardly projecting lugs 16 on which the 5 base of the baskets or containers rest. The baskets or containers are adapted to contain a suitable compound or material having properties of absorbing moisture and the impurities, such as carbonic acid gas, from 10 the products of combustion rising in the heater, and this material or compound is preferably in the form of small spheres or balls 17, although it may be in any other suitable form which will permit the products of combustion rising in the heating 15 chamber to pass through the body in the container, prior to escaping from the outlet openings into the room or inclosure.

In the form shown by Figs. 4 and 5, the 20 basket or container is modified and comprises a suitable plate 18, perforated as at 19, the same resting on and supported by the lugs 16. A handle 20 extends upwardly from the center of the plate to facilitate 25 the removal thereof from the heater. With this form of support the absorbing material or compound is not capable of removal from the heater in a body, but the same provides a more cheaply constructed support than 30 that disclosed in the other views.

It will be apparent that the products of combustion in their escape to the atmosphere are caused to pass through the body of purifying material which absorbs the impurities and moisture therefrom; also that 35 the walls 10 extended upwardly above the openings 9 retard the passage of the products to the atmosphere and cause the formation of pressure within the heating chamber which retards the rising of the gases of 40 combustion, giving the same a longer period to contact with the purifying compound. It is also apparent that access may be easily 45 had to the purifying material by simply removing the heads 8 which permit either the removing of the containers or support for the material or the examining thereof.

While I have illustrated the preferred embodiment of my invention in the form of 50 a heater of the radiator type and employing gas as fuel, it is to be understood that any form of heater, using any form of fuel, may be employed, just so long as the prod-

ucts of combustion before escaping therefrom are caused to pass through the body 55 of purifying material and means are provided for obtaining access to the interior of the heater for the renewal of the purifying material.

Having thus described my invention what 60 I claim is:—

1. A heater of the kind described and of the radiator type comprising a plurality of vertically arranged tubular sections of considerable height connected together at their 65 lower ends and each open at its upper end, a chambered cap-section detachably and freely resting on the open upper end of each section, a source of heat supply in the base of said sections, supporting lugs projecting 70 inwardly from their inner faces below their open end, and an open receptacle removably disposed in the upper ends of each section and supported by said lugs, said receptacle having openings in its walls and being 75 adapted to contain a purifying material, each of said caps having heat outlets in their side walls, and baffle plates within said caps forming trap pockets enveloping and extending above said outlets and open only 80 at their upper sides, said receptacles being removable through the upper ends of the sections when the caps are removed.

2. A heater of the kind described comprising a vertical tubular section having an 85 open upper end, a chambered cap-section detachably and freely resting upon the open upper end of said tubular section, a source of heat supply in the base of said tubular section, an open receptacle supported in 90 the upper end of said tubular section and adapted to contain a heat purifying material, said cap having a heat outlet in its side wall, and a plate in the cap and extending upwardly from the lower edge of said outlet to a point above the latter to form a trap pocket, said receptacle being removable 95 through the upper end of the tubular section when the cap is removed.

In testimony whereof I have signed my 100 name to this specification in the presence of two subscribing witnesses.

JOHN C. TATE.
